(57) **CLAIM**

I claim the ornamental design for a bag, preferably for bedding/ensemble, as shown.

DESCRIPTION

FIG. 1 is a front, top and right side perspective view of a bag, preferably for bedding/ensemble, showing my new design; FIG. 2 is a right side elevational view thereof;

FIG. 3 is a top plan view thereof;

FIG. 4 is a front elevational view thereof;

FIG. 5 is a rear elevational view thereof;

FIG. 6 is a left-side elevational view thereof; and,

FIG. 7 is a bottom plan view thereof.
